UNITED STATES PATENT OFFICE.

FREDERICK STICKEL, OF CHICAGO, ILLINOIS.

PUMP.

1,384,218.

Specification of Letters Patent. Patented July 12, 1921.

Application filed July 23, 1920. Serial No. 398,404.

To all whom it may concern:

Be it known that I, FREDERICK STICKEL, a citizen of the United States, and a resident of Chicago, in the county of Cook and State 5 of Illinois, have invented certain new and useful Improvements in Pumps, of which the following is a specification.

My invention relates to improvements in pumps and has special reference to manually operated air pumps for filling pneumatic 10 tires.

The object of my invention is to provide a combined pump and indicator by means of which the operator can see at all times the 15 pressure which has been produced in the tire without the necessity of changing any valve or connection.

Preferably I embody my invention in the form of a relatively large pump, which obviously can be one or two stage, and provide the pump with foot plates upon which the operator places his feet for holding the pump stationary during operations. Adjacent to the vertical cylinder of the pump I 20 arrange an indicating cylinder containing a spring pressed piston adapted to be moved against the spring pressure by the air pressure produced. The piston rod upon which the piston is mounted extends out through 25 the upper end of the indicating cylinder and I provide a pressure-indicating scale on the adjacent side of the pump cylinder adapted, in conjunction with the upper end of the piston rod, to show the air pressure produced.

Other features of my invention relate to an improved manner of admitting the air to the pump cylinder and to means for adjusting the tension of the spring for causing the indicator to accurately show the 30 pressure.

My invention will be more readily understood by reference to the accompanying drawings forming part of this specification, and in which:—

Figure 1 is a side elevation of a pump embodying my invention;

Fig. 2 is a longitudinal vertical section on the line 2—2 of Fig. 1;

Fig. 3 is a horizontal section on the line 50 3—3 of Fig. 2; and

Fig. 4 is a horizontal section of the pump

cylinder in the line 4—4 of Fig. 2 and showing the flap valve.

In said drawings, 1 is a pump cylinder. This cylinder is mounted rigidly at its lower 55 end in a base 2, to stand vertically. The base is provided with suitable flat extensions 3 upon which the operator can place his feet for holding the pump when in use. The cylinder 1 is open at its bottom and connects 60 with a passage 4 in the base 2 through which the air is delivered from the cylinder 1.

Mounted in the cylinder is a leather cup piston 5 arranged to compress the air as it is forced downwardly. The piston is mounted on the lower end of a piston rod 6 which extends through the cylinder and projects through a central guide opening 7 in a cap 8 secured to and closing the upper end of the cylinder 1. The outer end of the rod 6 has a 70 suitable handle 9 secured thereto. A transverse pin or stop 10 carried by the rod 6 prevents the piston 5 striking the base 2 at the lower end of the down stroke. The rod 6 is hollow from end to end having a central passage 11 for admitting air to the space below the piston 5 without the necessity of the air passing the periphery of the piston and I control the lower open end of the passage 11, through the rod 6, by a simple check valve 12. 75 This valve consists of a flat yielding closure member 13 preferably made of rubber or leather, mounted within the piston 5 and adapted to seat upon and tightly close the lower end of the tubular piston rod 6. The 80 closure member 13 is carried by a light flat spring 14 secured at one end to the piston head 5 by a screw 15, thus providing a flat check valve.

To avoid a back pressure or a vacuum in 90 the upper end of the cylinder 1, I provide a vent opening 16 in the tubular wall of the piston rod near its lower end. Atmospheric air can freely enter and escape from the upper end of the cylinder through this vent 95 opening, even though the fit of the rod 6 in the cap might be too close to allow this.

Mounted on the base 2 and standing up parallel with the cylinder 1, I arrange an auxiliary cylinder 17. The lower end of this 100 auxiliary cylinder is in communication with the passage 4 by means of a vertical passage

18 which is controlled by a check valve 19. The valve 19 as shown, being a ball check valve. The ball is adapted to close the passage 18 by gravity and to be lifted by air pressure beneath the valve. Between the valve and the cylinder 17 I arrange an outlet 20 controlled by a cock 21 and having a nozzle 22 adapted to be connected by a rubber hose 23 to the tire to be pumped up.

10 Within the cylinder 17 I provide a piston head 24 consisting of a leather cup piston 25 held in place on the lower end 26 of a piston rod 27. The rod extends up through the cylinder 17 and has a thin washer-like head 28 secured upon its upper, exposed end. The cup piston 25 is held against a fixed washer or collar 29 on the rod 27 by jam nuts 30. I close the upper end of the auxiliary piston 17 by a screw threaded collar 15 or abutment 31 which is adapted to be screwed down into the upper end of the cylinder. The abutment 31 is provided with a head 32 by which it can be readily adjusted.

25 Between the adjustable abutment 31 and the collar 29 on the piston rod 27 I arrange a compression spring 33 within the cylinder 17 which is adapted to resist the upward movement of the piston 25 under the influence of the pressure in the base produced by the pump.

For indicating the pressure produced I provide a scale 34 on the side of the pump cylinder 1, extending upwardly above the upper end of the auxiliary or indicating cylinder 17, the periphery of the thin head 28 on the piston rod 27 being adapted to indicate on the scale 34 the pressure produced.

40 In making my combined pump and indicator I calibrate the scale 34 with the use of a standard pressure gage connected to the delivery end of the device in a manner which will be well understood by those skilled in the art.

45 The interior of the auxiliary cylinder above the piston 25 is freely open to the atmosphere so that the piston can freely assume a position of balance between the pressure beneath it and the spring 33.

50 From time to time the pump can be compared with a standard pressure gage and if the spring has changed so that the indications are not accurate the tension of the spring can be changed or adjusted by means of the adjustable abutment 31 in an obvious manner.

55 For convenience I arrange the scale 34 both so as to be easily read right side up and wrong side up so that the one operating the pump can as readily read the indications when leaning over the pump in a position with his head hanging down as can one standing along side of the device.

60 It will be clear that as the indicating

cylinder is constantly in communication with the delivery passage of the pump the indications will at all times show the pressure of the air which is being delivered and if the delivery hose 23 is connected to a tire 70 this indicated pressure will be the pressure of the air in the tire.

It will be understood that no valves need be operated by hand or connections made or broken in order that the attained pressure in 75 the tire may be ascertained or observed.

As it will be obvious that many modifications of my invention will readily suggest themselves to one skilled in the art, I do not limit or confine my invention to the specific 80 constructions herein shown and described, except within the scope of the appended claims.

I claim:

1. In a tire pump, a foot plate, a pump 85 cylinder rising from the foot plate, an indicating cylinder also rising from the foot plate and arranged parallel and adjacent to the pump cylinder and shorter in length, a spring held plunger projecting out of the top of the indicating cylinder and adapted to be forced out by the pressure produced in the pump cylinder, a pressure scale on the pump cylinder above the indicating cylinder and adapted to coöperate with the outer end 90 of the plunger to indicate the pressure produced by the operation of the pump, and means adapted to freely connect the lower end of the indicating cylinder with a tire.

2. In a tire pump, a foot plate, a pump 100 cylinder upstanding from the plate, a vertical indicating cylinder alongside the pump cylinder, the plate having a passage connecting the lower ends of the two cylinders, a pressure tight piston in the indicating cylinder, a piston rod carried thereby and projecting through the top of the indicating cylinder, an adjustable head closing the upper end of the indicating cylinder, a compression spring in the indicating cylinder 110 between the piston and the adjustable head, and a pressure scale on the side of the pump cylinder above the indicating cylinder adapted to coöperate with the outer end of the piston rod to indicate the pressure produced by the pump, a check valve in the passage connecting the lower ends of the cylinders and means for delivering air from the lower end of the indicating cylinder to a tire.

3. In a device of the kind described, an indicating cylinder, a cup piston in the cylinder, a rod carrying the piston and projecting from one end of the cylinder, a spring in the cylinder surrounding the rod 125 and having its inner end against the piston, and an adjustable abutment at the outer end of the cylinder against which the upper end of the spring abuts for adjusting the tension of the spring.

4. The improvements herein described, a vertical pump, an auxiliary cylinder parallel therewith, and in communication therewith at its lower end, means adapted to be projected from the upper end of the auxiliary to indicate the pressure produced by the pump and a scale on the adjacent side of the pump cylinder for coöperation with said indicating means for showing the pressure, the pressure indicating figures on the scale 10 being arranged to be read in upright and in reversed position.

Signed at Chicago, Illinois, this 20th day of July, 1920.

FREDERICK STICKEL.
